UNITED STATES PATENT OFFICE.

EUGÈNE SCHNEIDER, OF LE CREUZOT, FRANCE.

TORPEDO-LAUNCHING TUBE.

1,024,424.

Specification of Letters Patent.

Patented Apr. 23, 1912.

Application filed May 15, 1911. Serial No. 627,160.

To all whom it may concern:

Be it known that I, EUGÈNE SCHNEIDER, a citizen of the Republic of France, residing at Le Creuzot, Saône-et-Loire, France, have 5 invented certain new and useful Improvements in or Relating to Torpedo-Launching Tubes, of which the following is a specification.

This invention relates to torpedo launching tubes.

Heretofore the launching of torpedoes has been effected by giving to the torpedo launching tubes a suitable direction relatively to the torpedo boat on which they are carried 15 and by maintaining the boat in a given direction during the operation. The maintaining of the direction of the tubes relatively to the torpedo boat and to the target aimed at necessitates two operators, one of 20 whom operates the sighting mechanism and follows the moving mark, while the other operates the tubes; if long and dangerous maneuvers are to be avoided it also entails keeping the torpedo boat in a constant direction 25 until the moment of launching and does not permit of the rapid alteration of the firing data. The support for torpedo launching tubes which forms the subject of the present invention obviates these defects.

With this object it comprises a carriage proper movable about its axis and upon the platform of which torpedo launching tubes are fixed. This carriage is characterized by the fact that a periscopic sighting apparatus 35 is mounted thereon parallel with the axis of rotation of the carriage and that it likewise carries in or on a sleeve projecting beneath the platform a portion of the elements of the training mechanism; one of the supplementary parts of this mechanism is carried by a fixed circular saddle upon which the carriage is able to run upon a circle of rollers that are interposed. The whole thus 40 constitutes a support similar to a gun carriage with central pivot with eyepiece and means for operating the sighting and training mechanism, the whole projecting beneath the platform thereby enabling one and the same operator who is constantly 45 sheltered to modify at any moment the direction of the tubes for reaching a movable target and this whatever the changes of direction of the torpedo boat may be.

In order that the said invention may be 50 more clearly understood and readily carried into effect I will describe the same more

fully with reference to the accompanying drawings in which:—

Figures 1 and 2 are two sectional elevations on two planes at right angles passing through the axis of the support, showing one constructional form of the invention arranged for a single torpedo launching tube. Fig. 3 is a partial plan corresponding to Fig. 1. Fig. 4 is a cross section on the line A—A 60 in Fig. 2. Fig. 5 is a sectional plan on the lines B B, C C in Fig. 2. Fig. 6 is a general longitudinal sectional elevation of another constructional form of the invention adapted for twin torpedo launching tubes. Fig. 7 65 is a corresponding cross sectional elevation. Fig. 8 is a partial sectional plan on the line A—A in Fig. 7. Fig. 9 is a partial elevation corresponding to Fig. 7 and showing in front elevation the eyepiece of the periscopic 70 apparatus.

Referring to the construction shown in Figs. 1-5, the torpedo launching tube *a* of any known type is attached to the platform *b* of the carriage proper and projecting from the lower face of said platform are two vertical cylindrical and concentric members *b'* *b''*. The member *b'* of larger diameter carries at its lower end the track *b³* upon which the carriage rests on a ring 80 of conical rollers *c*. Radiating ribs *b⁴* connect the cylindrical members *b'* *b''* the plate *b* and the track *b³*. The member *b'* carries two arms *b⁷*, the upper face of which is flush with the platform and upon which the 85 tube *a* is fixed for example by bolting it by means of lugs *d* on the assembling flanges *a'*. By the intermediary of the ring of rollers the carriage proper rests upon a saddle *e* fixed to the deck and in a vertical 90 cylindrical part *e'* in which it is centered by a collar or projection *b⁵* cast with the track *b³*, a friction ring *f* of bronze being fixed to the said collar *b⁵*. The lubrication 95 of this ring is provided for by means of a tube *g* (Fig. 2) opening to the exterior. A second crown *b⁶* carried by the outer cylindrical member *b'* at its lower edge 100 forms a hook for retaining the carriage proper upon the saddle and at the same time 105 protects all the inner parts from bursting shells and the penetration of sea-water. The carriage proper *b* carries a certain number 110 of the elements of the training mechanism for the torpedo launching tube *a* a supplementary element of this mechanism being fixed upon the saddle and constituted in

the example here illustrated by a toothed crown h . The latter meshes with an intermediate wheel i (Figs. 2, 3 and 4) rotating freely upon a shaft j carried by the carriage. The wheel i meshes with a pinion k carried by a vertical shaft m upon which a worm wheel q is keyed. The shaft m is journaled in bearings n and o carried respectively by the inner cylindrical member b^2 of the carriage and by the lower extremity of a metal sleeve x fixed beneath this cylindrical member. The said sleeve itself carries a box p forming a supporting bearing for a screw r meshing with the wheel q and adapted to be operated by a hand wheel s provided with a handle s' . By rotating the latter the wheel i is caused to run upon the toothed ring h by the intermediary of the transmission $q m k$ and the carriage proper and the tube a carried by it participate in this movement. In the carriage there is likewise mounted a periscopic and panoramic sighting apparatus t of known construction, the device t' of which receives the luminous rays and may be operated by means of a hand wheel t^2 within reach of the marksman. It will of course be understood that the carriage may be provided with various other accessories and in particular means for actuating the firing mechanism mounted on the breech of the tube a .

In the construction shown in Figs. 6-9 the carriage proper carries only one of the elements of the training mechanism of the tubes a , that is to say the toothed ring h . The saddle e forms a bearing for the upper end of a shaft m upon which a pinion k directly in mesh with the ring h is keyed. The lower end of the shaft m carries a worm wheel q and turns in a box p fixed to the boat and which forms supporting bearings for a screw r meshing with the said worm wheel. It will readily be understood that by operating the handle s keyed upon the screw r , the toothed ring h and consequently the carriage proper are caused to rotate by the intermediary of the transmission $q m k$. The sighting apparatus t which as in the preceding example is a panoramic periscope is arranged in the axis of the support between the two tubes a which protects it against external influences. At its lower part in proximity to the eyepiece t^3 the apparatus comprises a graduated conical drum

u moving simultaneously with the carriage in a fixed casing v carrying an index w .

The form of support described obviates the defects enumerated above and also the crowding of the decks with the circular track heretofore employed. Even in the case of twin tubes the carriage does not exceed the width of the combined tubes. The marksman can always keep his eye fixed upon the objective while the commander of the torpedo boat can modify his direction in order to follow the best course. In particular the marksman can rapidly modify the training in accordance with fresh firing data (change of speed or direction of the objective) and arrange the torpedo launching tubes in the proper direction.

What I claim and desire to secure by Letters Patent of the United States is:—

1. In combination, a revoluble torpedo carriage provided with a torpedo launching tube fast thereto, and adapted to be mounted on the deck of a vessel, training mechanism sheltered below said carriage and beneath the deck for turning said carriage and training said tube on an object and a periscopic sighting device mounted on said carriage and means for operating said device below said platform whereby the sighting of the object and aiming of the torpedo tube is made independent of the direction of the vessel's course.

2. In combination, a revoluble torpedo carriage adapted to be mounted on deck of a vessel comprising a platform adapted to support a torpedo launching tube and a sleeve depending from said platform and provided with training mechanism, a circular saddle for revolvably supporting said platform and having a fixed rack engaging said training mechanism and a periscopic sighting device mounted on said carriage and having means for operating the same sheltered below said platform all arranged whereby the sighting of the object and aiming of the torpedo tube is independent of the direction of the vessel's course.

In testimony whereof I have affixed my signature in presence of two witnesses.

EUGÈNE SCHNEIDER.
